UNITED STATES PATENT OFFICE

2,365,770

CONCRETE SHIP

Ross Nebolsine, Seacliff, N. Y.

Application April 21, 1943, Serial No. 483,845

6 Claims. (Cl. 114—65)

The object of the invention is to provide a concrete ship of normal exterior form and which will overcome serious defects in ships of this character heretofore proposed. These defects in concrete ships include as a major factor lack of adequate resistance to the heavy and reversible longitudinal bending moments and accompanying shearing stresses which are imposed upon the ship's hull in heavy weather.

The characteristic of my construction is the provision of a "back bone" composed of a unitary structure of hollow or box girders extending substantially from the bow to stern of the hull and from bottom to main deck positioned centrally of the hull structure, this "back bone," in the preferred form, being tied to and coacting with a steel-reinforced deck and the bottom shell and preferably to a plurality of box girders, the construction adequately resisting the said longitudinal bending moments. The said longitudinal and centrally disposed integral combination of hollow or box girder incidently serves with the transverse box girder constructions to divide the hull into a plurality of holds or water-tight compartments and provide buoyancy chambers which are ideal in refrigerated ships because the assemblies of box girders are hollow and are of such character that access to the holds may be reached via the box girder constructions themselves through the deck and through side manholes wherever desired. Also the hollow girder construction provides space for piping and wiring in addition to the safety factor in event of puncture of the outside shell.

The above and further objects of the invention will be described with reference to the accompanying drawings, in which:

Figure 1 is a view in elevation, showing the embodiment of the invention in a cargo ship.

Figure 2 is a plan view, partly in horizontal section, on the lines 2—2, Figure 1.

Figure 3 is a transverse enlarged section on the line 3—3, Figure 2.

Figure 4 is a fragmentary detailed view showing a portion of the central longitudinal box girder construction and that area communicating with one of the transverse box girder constructions and illustrating access thereto from the deck and from one girder construction to another.

Figure 5 is a fragmentary sectional view, taken vertically through a side and part of the bottom of a modified form of hull in which the bottom is cellular.

Referring to the drawings, I have shown in Fig-

ure 1 a cargo ship 1 having deck hatches 2 for a deck 3.

Reference to Figure 2 in connection with Figures 3 and 4, will show that the outer surfaces of the hull are composed of box girders joined to form a unitary structure throughout the outer surface of the hull with the exception of the bottom. Each box girder consists of the outer wall of the ship hull 1, as to an area thereof, and inwardly spaced vertical wall 4 and a plurality of spaced web members 5 connecting the walls at 1 and 4.

As shown in Figure 3 the hull "back bone" consists of a centrally disposed longitudinally extending box girder construction which extends the entire length of the hull and which consists of spaced parallel walls 6 and 7 and connecting webs 8. As to be noted from Figure 3 the said "back bone" box girder construction merges into the bottom of the hull indicated at 9, and it also merges into the deck 3, being integral with the hull bottom and deck.

The major number of webs 5 and 8 are apertured so that walk-ways are provided for movement of men longitudinally of the box girders of the "back bone" or box girders of the hull construction per se. However, at predetermined places in the said box girder construction, imperforate transverse webs are provided, as indicated at 10, 11, 12, 13, and also at other areas. Thus should the hull be pierced at any point, the incoming water will be localized in an area bounded at each end by the imperforate webs.

A plurality of spaced transverse box girder constructions are employed, each consisting of spaced and opposed walls 14, 15, which merge into the walls of the "back bone," the inner walls of the box girders forming the shell of the hull, including the bottom, and also the deck 3. The opposed walls 14, 15, of the transverse box girder constructions are connected by spaced perforated webs 16, each series of these perforate webs being bounded at its ends by imperforate webs 17.

The deck 3 will be provided with a plurality of manholes 18 placed directly over the transverse box girder constructions. Thus members of the ship's staff or fitters may have access to each box girder section bounded by imperforate webs, may pass from the various sections of the transverse box girder constructions to the various sections of the "back bone" and also to the various sections of the box girder constructions at the sides of the hull as indicated, for example, by the arrows in Figure 3. If desired, water-tight doors may be provided in the holds for lateral

communication between any hold or holds and any contiguous box-like girder construction, whether transverse or longitudinal.

It will be seen by reference to Figures 3 and 5 that the deck, the hull bottom and the various box girder constructions are reinforced with steel rods or the like as indicated at 3x and that the said members are all merged into one unitary construction providing a series of liquid-tight holds, enabling the ship to be converted readily from use as a freighter or bulk carrier in the sense of solid material, to use as an oil carrier or as a combined general freighter and oil carrier.

The provision of the central longitudinally extending box girder "back bone" provides an ideally disposed support for erecting masts and booms employed in loading and unloading cargo. Also, and as an important factor, the said "back bone" gives strong support to the hull for side launching with marine railways.

Equally important to the above, is the function of the "back bone" in so taking up stresses particularly heavy and reversible longitudinal bending moments, so that reinforcing rods of steel and other reinforcing metallic members may be conserved and thicknesses of hull walls reduced. In fact, the steel reinforced construction of the deck and bottom is, for the first time in hull structures of the present type, enabled to adequately resist lengthwise bending moments with the provision of relatively thin walls. For example, the walls 1 and 4, reinforced in the usual manner by steel rods or equivalent reinforcement, will be adequately strong in my hull construction when of 3-3½".

In building the hull and its constituent box girder constructions, the metallic reinforcing members may be supported by pins or other supporting means on the outside of forms, and the concrete blown by pressure onto the outside of the forms, which forms are pulled up before the deck is formed or placed. In this manner the density of the concrete is so increased that great strength is provided and, at the same time, the process of construction is simplified.

Extending from side to side of the longitudinal box girder constructions, and preferably lying at both bottom and under-deck position, concrete girders, plain or steel reinforced, may be positioned, as indicated at 19, Figures 2 and 3. It will also be understood that various modifications may be made in the form and arrangement of the elements illustrated and described without departing from the spirit of the invention.

Having described my invention, what I claim and desire to secure by Letters Patent is as follows:

1. In a concrete ship, and in combination with a hull having sides consisting of hollow girders, a bottom and a deck, of a back bone construction consisting of a hollow girder construction extending substantially from end to end of the hull, longitudinally and centrally thereof and tied to the bottom and deck.

2. In a concrete ship, and in combination with

a hull having sides consisting of hollow girders, a bottom and a deck, of a back bone consisting of a hollow girder construction extending substantially from end to end of the hull, longitudinally and centrally thereof and tied to the bottom and deck, and a plurality of spaced transversely extending hollow girders tied to said back bone and to the hollow box girders, dividing the hull into a plurality of holds positioned at opposite sides of the back bone.

3. A concrete ship construction in accordance with claim 1, in which the deck is of reinforced concrete construction merging into and integral with reinforced concrete walls of both the hollow girder side construction of the hull and the walls of the hollow girder constructions comprising the back bone.

4. A concrete ship constructed in accordance with claim 1, in which the hollow girders are formed with spaced major concrete walls and series of transverse internal webs, each series including a plurality of perforate webs separated as to communication by imperforate webs, providing a plurality of water-tight compartments extending both longitudinally and transversely of the hull.

5. In a concrete ship, and in combination with a hull having sides consisting of hollow girders, a bottom and deck, of a back bone construction consisting of a hollow girder construction, extending substantially from end to end of the hull, longitudinally and centrally thereof and tied to the bottom and deck, a plurality of spaced transversely extending hollow girders tied to the said back bone and to the side hollow girders, dividing the hull into a plurality of holds positioned at opposite sides of the back bone, the hollow girders being formed with spaced major concrete walls and transverse internal webs, including a plurality of series of perforate webs, each series of perforate webs being bounded at its ends by imperforate webs, providing a plurality of water-tight compartments extending both longitudinally and transversely of the hull, the deck being provided with a plurality of spaced manholes, disposed over the hollow transverse girders for access to a plurality of the said water-tight compartments.

6. In a concrete ship, and in combination with a hull having sides consisting of hollow girders, a bottom and deck, a plurality of spaced transversely extending hollow girders tied to the side hollow girders, dividing the hull into a plurality of holds, the hollow girders being formed with spaced major concrete walls and transverse internal webs, including a plurality of series of perforate webs, the series of perforate webs being separated by imperforate webs, providing a plurality of water-tight compartments extending both longitudinally and transversely of the hull, the deck being provided with a plurality of spaced manholes, disposed over the hollow transverse girders for access to a plurality of the said water-tight compartments.

65 ROSS NEBOLSINE.
